(57) **CLAIM**

The ornamental design for a rolled medium holder for cutting plotter as shown and described.

DESCRIPTION

FIG. 1 is a front perspective view of a rolled medium holder for cutting plotter showing our new design in a closed state; FIG. 2 is a rear perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; FIG. 9 is a perspective view thereof in a use state; FIG. 10 is a front elevation view thereof; and, FIG. 11 is a top plan view thereof.

The broken lines depict portions of the cutting plotter that form no part of the claimed design.

1 Claim, 11 Drawing Sheets
